(57) **CLAIM**

The ornamental design for an adjustable bed foundation with cover having contrasting appearances, as shown and described.

DESCRIPTION

FIG. 1 is a perspective view of adjustable bed foundation with cover having contrasting appearances in accordance with a first embodiment of the present invention;

FIG. 2 is a top view of the adjustable bed foundation with cover having contrasting appearances of FIG. 1;

FIG. 3 is a perspective view of the adjustable bed foundation with cover having contrasting appearances of FIG. 1 with the foundation in an articulated position;

FIG. 4 is a perspective view of adjustable bed foundation with cover having contrasting appearances in accordance with a second embodiment of the present invention;

FIG. 5 is a top view of the adjustable bed foundation with cover having contrasting appearances of FIG. 4; and,

FIG. 6 is a perspective view of the adjustable bed foundation with cover having contrasting appearances of FIG. 4 with the foundation in an articulated position.

The broken lines shown in the Figures illustrate portions of the adjustable bed foundation with cover having contrasting appearances and form no part of the claimed design.

The dashed lines in FIGS. 3 and 6 represent folds in the cover and do not represent surface ornamentation.

The light stippling shown in the Figures indicates a first area of the cover and the dark stippling indicates a second area of the cover that has contrasting appearances as compared to the first.
